UNITED STATES PATENT OFFICE.

JOHN WESLEY McKNIGHT, OF HANOVER, PENNSYLVANIA, ASSIGNOR TO HANOVER GAS REGENERATING COMPANY, A CORPORATION OF PENNSYLVANIA.

COMBINED COCK AND SUPPORT FOR CLUSTER GAS-BURNERS.

No. 845,970.

Specification of Letters Patent.

Patented March 5, 1907.

Application filed August 13, 1904. Serial No. 220,627.

To all whom it may concern:

Be it known that I, JOHN WESLEY McKNIGHT, a citizen of the United States, residing at Hanover, in the county of York and State of Pennsylvania, have invented certain new and useful Improvements in a Combined Cock and Support for Cluster Gas-Burners; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to a combination cock and burner for incandescent and other gas-burners; and it has for its object to provide an improved construction whereby a series of burners or lights may be turned out in succession, so that any desired number of the series of burners may be employed for illuminating or other purposes with the minimum of friction and maximum of ease at whatever distance the burners may be located from the cock. It also has for its object to provide, in combination with such cock and burner mentioned, a continuously-lighted burner for igniting at the proper time a pilot-burner, from which the series of the cluster of burners may be lighted, and in which the pilot-burner will be automatically extinguished after serving its purpose of lighting the cluster of burners.

To the accomplishment of the foregoing and such other objects as may hereinafter appear, the invention consists in the features hereinafter particularly described and then sought to be clearly defined by the claims, reference being had to the accompanying drawing, forming a part hereof, and in which—

Figure 1 is a front elevation of the combined cock and burner embodying my invention. Fig. 2 is a side elevation at right angles to Fig. 1 with parts in section. Fig. 3 is a plan view of Fig. 1. Fig. 4 is a horizontal section through the ball or spherical body of the cock with parts in full lines. Fig. 5 is a vertical section through the by-pass valve of the pilot-burner, and Fig. 6 is a diagrammatic view of the channels and terminals formed in the tapering plug of the main valve for supplying gas to the series of

burners and by means of which they may be extinguished in succession.

In the drawing the numeral 1 designates a ball or globular body portion, through the central portion of which is bored a tapering opening 2, forming the seat for a tapering plug-valve 3, and through the body portion 1 a number of ports or passages 5 are bored, so as to open into the central bore 2, and designed to have communicate therewith the supporting-arms, which will support or have connected therewith the burners designated by the numeral 6 and which may be of any approved pattern or type, said supporting-arms being designated by the letters *a*, *b*, *c*, and *d*, of which four are illustrated, but of which any desired number may be employed, from each of which will lead one of the ports 5, which open into the central bore 2 and which will be controlled by the tapering plug 3, which will have channels and terminals formed in its body, as hereinafter described, so as to enable the ports or passages 5 to be closed in succession, or to permit all of them to be opened, so as to supply gas to all of the burners of the cluster. The ball-body 1 will have a bore 7 made partially through it to receive a gas-supply pipe or tube 8, and the base or bottom of the bore 7 will be formed with an oblong opening 9, opening into the central bore 2, and in the bottom of the ball-body 1 will be formed a bore 10, extending partially into the same to receive a tube or nipple 11 to adapt it to be coupled or connected to a support or standard for sustaining the ball-body.

The tapering plug-valve 3 is formed with a circumferential groove or duct 12, which extends partially around the plug and which has leading therefrom longitudinally of the plug the ducts or passage-ways 13, 14, 15, and 16, the passage-ways 13 and 16 having laterally-extending terminals 17 and 18. When the tapering plug 3 is turned to the limit of its movement in one direction—for instance, to the right—by pulling on the chain 19, attached to a lever 20, secured to the plug, the gas will flow to all of the burners, and the flame will be at all of them. By turning the plug to the left by pulling on the opposite chain 21, attached to the lever 20, the several burners in succession may be extinguished, the burners being extinguished in alterna-

tion from opposite sides of the plug—that is, the burner attached to the arm *a* being the first one extinguished, then the burner connected with the arm *b* is extinguished, then 5 the burner connected with the arm *c*, and then the burner connected with the arm *d*, thus causing the burners directly opposite each other to be extinguished in succession, so that if the burners be used for illuminating 10 purposes the light or flame will be from opposite sides of the ball-body, thus causing a better distribution of the flame or light than would be if the lights extinguished were on the same side. I have illustrated only four 15 burners constituting the cluster; but it is obvious that the number may be increased and the passage-ways leading thereto be formed so as to supply the gas to the additional burners and cause the burners to be extinguished in succession one at a time as desired. The ball-body will be provided with an index-scale—for instance, such as A—and the tapering plug will be provided with an index-finger B, so as to indicate the number of 20 burners lighted or extinguished by the position of the index-finger in relation to the scale, which is of advantage if the burners be at a more or less remote point from the controlling-cock, and this index-finger will also 25 serve as a stop to limit the movement of the plug-valve by being brought against the shoulder at the limit of movement of the finger in opposite directions, said shoulders being designated by the numeral 22.

30 For the purpose of lighting the series of burners from a pilot-light I provide a Bunsen burner 23, which will connect by a pipe 24 with the nipple or coupling 8 of the gas-supply pipe, which Bunsen burner will have a 35 flame continuously burning, the supply of gas to said burner being controlled by a valve 24. Adjacent to this burner will be the pilot-light 25, which will connect with the nipple or coupling 8 by a pipe 26, thus forming a bypass 40 from the nipple 8 to the pilot-light. This pilot-light will be provided with a controlling-plug 27, whose movement may be limited by a set-screw or stop-pin 28. The plug will also be provided with a lever 29, 45 which at one end will be connected by a chain 30 with the chain 19 of the lever 20 of the main cock to the ball-body, the opposite end of the lever 29 being connected by a spring 31 with the ball-body 1. With the parts 50 thus assembled, when the main lever 20 is moved to turn the main controlling-valve 3 for the supply of gas to the series of burners the pilot-lever 29, through the chain connection 30, will be turned so as to permit a supply 55 of gas to the pilot-light, and the jets of gas issuing from the pilot-burner through the orifices 32, formed so as to deflect the jets, will be directed toward the series of burners of the cluster, and the jets issuing from the pilot-burner being ignited by the flame from the 60

Bunsen burner will cause the gas issuing from the cluster of burners to be ignited, and when tension on the connecting-chain 30 is released the spring 31 will retract the pilot-lever 29 and turn its plug 27 so that the flame from the pilot-burner will be diminished or entirely extinguished, according as the plug 27 is allowed a greater or less movement by the set-screw or stop-pin 28. The pilot-light is thus brought in operation at the proper time 70 to ignite the gas issuing from the cluster of burners and then has its flame diminished or extinguished, so as to avoid the formation of carbon on the cluster of burners, which would be liable to occur if the pilot-light was thus 75 not controlled. The burners 6 of the several arms extending from the ball-body 1 may be approximately near to the ball-body; but under the construction described they may be more or less remote from said body by a prolongation of the arms *a b c d* extending from the ball-body, and in such case the Bunsen burner and the pilot-light would be proportionately removed from the ball-body by a simple prolongation of the pipes 24 and 26, 80 which connect the Bunsen burner and the pilot-light, respectively, or rather the portions of said pipes to which the burner-tips will be connected, and when such is the case the index-finger and scale before referred to 85 will indicate the number of burners that may be ignited or extinguished.

I have illustrated and described with particularity the preferred details of construction and arrangement of the several parts; 100 but it is obvious that changes can be made therein and essential features of my invention be retained.

Having described my invention and set forth its merits, what I claim is—

1. A combined cock and support for a cluster of burners comprising a body supporting a series of burner-supporting arms and formed with an inlet for gas and ports leading to the series of arms, and a controlling-plug fitting in said body and formed on its exterior with a central passage-way to communicate with the gas-inlet and having passage-ways leading therefrom to each of said ports, said passage-ways being formed so 110 that by turning the plug they will be consecutively moved out of communication with said ports to cut off in succession the supply of gas thereto, in combination with the pilot-burner provided with a controlling-valve for 115 igniting the cluster of burners therefrom, and a Bunsen burner for igniting the gas issuing from the pilot-burner, substantially as described.

2. A combined cock and support for a 125 cluster of burners comprising a body supporting a series of burner-supporting arms and formed with an inlet for gas and ports leading to the series of arms, and a controlling-plug fitting in said body and 130

formed on its exterior with a central passage-way to communicate with the gas-inlet and having passage-ways leading therefrom to each of said ports, said passage-ways being 5 formed and so located in relation to the ports leading to the several burners that by turning the plug the burners will be extinguished in consecutive alternation from opposite sides of a line drawn centrally through the 10 body-support whereby when any two burners are lighted they will be burners opposite to each other and on opposite sides of said line, in combination with a pilot-burner provided with a controlling-valve for igniting 15 the cluster of burners, and a Bunsen burner for igniting the gas issuing from the pilot-burner, substantially as described.

3. A combined cock and support for a cluster of burners comprising a body sup- 20 porting a series of burner-supporting arms and formed with an inlet for gas and ports

leading to the series of arms, and a controlling-plug fitting in said body and formed with a central passage-way to communicate with the gas-inlet and having passage-ways leading 25 therefrom to each of said ports, said passage-ways being formed so that by turning the plug they will be moved out of communication with said ports to cut off the supply of gas thereto, in combination with the pilot- 30 burner provided with a controlling-valve for igniting the cluster of burners therefrom, and a Bunsen burner for igniting the gas issuing from the pilot-burner, substantially as described. 35

In testimony whereof I affix my signature in presence of two witnesses.

JOHN WESLEY McKNIGHT.
